AIR TEMPERING EQUIPMENT

William Bunch, Grand Prairie, Tex.

Application October 6, 1954, Serial No. 460,579

5 Claims. (Cl. 261—10)

This invention relates to air conditioning and air 15 tempering equipment and more particularly to a self-contained unit that will be compact and easy to handle and transport. It has among its objects to provide a new and improved air tempering unit that will avoid, one or more of the disadvantages and limitations of the prior art. Another object of the invention is to provide a new and improved air tempering unit, that will be arranged for cooling air to be dispersed in a room or chamber, without the use of conventional refrigerating equipment normally essential in apparatus of this nature.

A further object of the invention is to provide a new and improved air tempering unit employing evaporative cooling principles. An additional object of the invention is to provide a new and improved air tempering unit that will not only cool the air that is dispersed by it, but will have control of the moisture content therein.

Still another object of this invention is to provide a new and improved air tempering unit that will be simple in construction, economical to manufacture and maintain, and effective in operation, as well as afford a filtering arrangement in its structure to remove dust and objectional matter, as the air is passed through the device and before it is distributed thereby.

Other objects of the invention will become apparent as the invention is more fully set forth. The provision of a unit or system for the conditioning of air in a room or public space, has become an important adjunct in modern civilization. However the cost of an installation for this purpose and its operation is high, too much to appeal to families of moderate means.

This invention is intended to meet the conditions and resulting demand for a reasonably priced installation, having a low maintenance and operating cost. It is feasible to make the system in small or moderate sized units and include automatic features as additional conveniences.

The partial vacuum induced by the exhaust pump, in conjunction with a suitable regulating valve is employed to give a balancing effect in the cooling results. This arrangement avoids the apparatus required in a conventional refrigerated system and its expensive sundries. The recirculating coil employed in this invention is an advantageous feature in that it stretches the temperature limits over a considerable range. This unit can be utilized in cold and warm climates. This invention emphasizes in its operation: (1) a vacuum effect on the treated air; (2) control of the amount and pressure of the entering air by a regulating valve; (3) a heat interchanger coil for varying the cooling action; (4) and a humidity control for the dispersed air and (5) a panel for creating a bubbling system of streams through water, evenly and fully distributed for producing a humidifying, cooling and moisture saturation effect; (6) a comparatively noiseless action.

2

For a better understanding of the invention and the objects thereof, reference is made to the accompanying drawings, wherein a preferred form of the invention is indicated. These drawings in conjunction with the following description, illustrate the invention, explain its principles and explain its method of operation.

Referring to the drawings:

Figure 1 is a sectional elevation taken longitudinally through an air tempering unit on line 1—1 of Figure 2, together with its connections, and embodying this invention;

Figure 2 is a transverse sectional elevation taken on line 2—2 of Figure 1; and

Figure 3 is a view in perspective of the filtering and air distributing panel used in this embodiment.

Similar reference characters refer to the same parts throughout the drawings:

In the construction shown in the drawings, a cabinet 10 of formal rectangular contour and suitable material, thickness, and strength is provided to contain the various items that make up the equipment of an air tempering unit. The interior of the cabinet includes an air distributing chamber 11 near the bottom; a water cooling and coil section 12, perforated baffles and drip plates 21 and 22, and an upper secondary chamber 14, for holding the tempered air ready for dispersal.

The chamber 11 is separated and partitioned off from the section 12 by a relatively thin perforated panel 15. Its perforations 16 are evenly distributed over the panel 15, and are made very minute. The perforations are small enough to avoid leakage (because of surface tension) of appreciable quantities of water resting on the panel 15. The chamber is fed with air under pressure through a piping inlet connection 17 and after accumulating in the chamber, passes it in fine needle-size streams through the holes 16, into the water section 12. The air continues through the water 18 and fills the space 20 above the latter. Then a suction or vacuum device, pump or exhaust fan 19 mounted on the outer top surface of the cabinet is operated and provides a partial vacuum in the space 20. This induces the air to flow out of the space with considerable speed and give up enough heat to reduce its temperature a considerable number of degrees. As the air leaves the space, it passes between a set of baffles or drip plates 21 and 22. The lower baffle 22 has perforations 23 to allow any excess water condensing out of the air, to accumulate on it and drip back into the water 18 below. The device 19 is driven by a motor 40.

The baffle plates are placed relatively close to one another and serve to squeeze or compress the air stream as it passes to the upper chamber 14 for the tempered air. From the upper chamber 14 the air passes through the

55 main outlet piping connection 24 to the suction device, pump or exhaust fan 19 and is discharged into the piping 25. The piping carries the air to a diversion valve 26 of the three-way type. The valve 26 can be operated to send the air into an outlet 27 from a pipe line 28 connected to it.

At the outlet, the air is distributed into a room (not shown) intended to be supplied by it and cooled. If the valve 26 is operated in another direction it diverts the air through the piping connection 29 at the water pool in section 12. The air continues through the tubular copper coil 30 which is cooled further by the water 18, already cooled by the evaporative action of the air passing through it under pressure and vacuum. Leaving the tubular coil 30 through the connection 31, it enters into the piping 32 and flows to an outlet 33 in another selected room, suitably located nearby.

Service connections through water piping 34 fill the water section to a predetermined level, and can be drained

through the piping 35. A float and valve mechanism 36 of conventional type keep the water at the proper level.

In order to keep the pressure of the air flowing into the air distributing chamber at the proper amount, a suitable regulating valve 37 is inserted in the service line 38 and controls the flow of air through the unit. There are certain adjustments made and rendered practical by the balancing of the suction or vacuum device 19 against one another, in conjunction with the conditions imposed by the water, panel, baffles and piping. When the proper balance is acquired the unit tempers the air passing through and provides the necessary temperature and humidity desired or selected before the air is distributed at the outlets. Various channels such as radiators and the like can be utilized for the delivery of the tempered air from the device. The term "partition" is usable in this specification to include in its meaning, the drip plates or baffles 21 and 22, as well as the panel 16, employing it in a generic way.

The arrows used on the drawing enable the observer to follow the path of the air through the system.

While but one form of the invention is indicated in this application it is not desired to limit this application for Letters Patent to such form, as it is appreciated that other forms and constructions could be designed and used that would use the same principles and come within the scope of the appended claims.

Having thus described the invention what is claimed is:

1. An air tempering unit comprising in combination, a cabinet, minutely perforated panel disposed across said cabinet dividing it into an air distributing chamber and a secondary chamber; baffles staggered across said secondary chamber for diverting air drawn from said first mentioned chamber through the perforations in said panel into said secondary chamber, said panel being adapted to support a quantity of water thereon without it appreciably leaking through said perforations but allowing air under pressure to pass upwardly through the panel and water and be humidified thereby and tempered by evaporation before continuing by the baffles; a main inlet for supplying air to the distributing chamber, a main outlet for the outflow of the tempered and humidified air, and a device for inducing the air to flow through the chambers from the main inlet to the main outlet under pressure, with the addition of a tubular coil disposed in the secondary chamber to be immersed by said water, connections between the said outlet and said coil for transmitting the tempered air therethrough and an additional outlet for exteriorly dispersing the air after it passes through the coil.

2. An air tempering unit comprising in combination, a cabinet, a minutely perforated panel disposed across said cabinet dividing it into an air distributing chamber and a secondary chamber; baffles staggered across said secondary chamber for diverting air drawn from said first mentioned chamber through the perforations in said panel into said secondary chamber, said panel being adapted to support a quantity of water thereon without it appreciably leaking through said perforations but allowing air under pressure to pass upwardly through the panel and water and be humidified thereby and tempered by evaporation before continuing by the baffles; a main inlet for supplying air to the distributing chamber, a main outlet for the outflow of the tempered and humidified air, and a device for inducing the air to flow through the chambers from the main inlet to the main outlet under pressure, with the addition of a tubular coil disposed in the secondary chamber to be immersed by said water, connections between the said outlet and said coil for transmitting the tempered air therethrough and an additional outlet for exteriorly dispersing the air after it passes through the coil with the addition of a valve for selectively controlling the passage of the tem-

pered air through the coil and to the exterior atmosphere.

3. An air tempering unit comprising in combination a cabinet, a minutely perforated panel disposed across said cabinet dividing it into an air distributing chamber and a secondary chamber; baffles staggered across said secondary chamber for diverting air drawn from said first mentioned chamber through the perforations in said panel into said secondary chamber, said panel being adapted to support a quantity of water thereon without it appreciably leaking through said perforations but allowing air under pressure to pass upwardly through the panel and water and be humidified thereby and tempered by evaporation before continuing by the baffles; a main inlet for supplying air to the distributing chamber, a main outlet for the outflow of the tempered and humidified air, and a device for inducing the air to flow through the chambers from the main inlet to the main outlet under pressure, with the addition of a tubular coil disposed in the secondary chamber to be immersed by said water, connections between the said outlet and said coil for transmitting the tempered air therethrough and an additional outlet for exteriorly dispersing the air after it passes through the coil with the addition of a valve for selectively controlling the passage of the tempered air through the coil and to the exterior atmosphere with the addition of means for supplying and draining the water in the secondary chamber and means for automatically controlling the supplying means.

4. An air tempering unit comprising in combination a cabinet, a minutely perforated panel disposed across said cabinet dividing it into an air distributing chamber and a secondary chamber; baffles staggered across said secondary chamber for diverting air drawn from said first mentioned chamber through the perforations in said panel into secondary chamber, said panel being adapted to support a quantity of water thereon without it appreciably leaking through said perforations but allowing air under pressure to pass upwardly through the panel and water and be humidified thereby and tempered by evaporation before continuing by the baffles; a main inlet for supplying air to the distributing chamber, a main outlet for the outflow of the tempered and humidified air, and a device for inducing the air to flow through the chambers from the main inlet to the main outlet under pressure, with the addition of a tubular coil disposed in the secondary chamber to be immersed by said water, connections between the said outlet and said coil for transmitting the tempered air therethrough and an additional outlet for exteriorly dispersing the air after it passes through the coil with the addition of a valve for selectively controlling the passage of the tempered air through the coil and to the exterior atmosphere with the addition of means for supplying and draining the water in the secondary chamber and means for automatically controlling the supplying means with the device for inducing the air flow including a vacuumatic mechanism adjacent the main outlet and connected therewith to produce a suction within the cabinet to draw air from the main inlet through the distributing chamber, the perforations in the panel, through the water into the space above in the secondary chamber, against the baffles to remove excess particles of water and collect and drain them back into the water, and thence to the main outlet.

5. An air tempering unit comprising in combination a cabinet, a minutely perforated panel disposed across said cabinet dividing it into an air distributing chamber and a secondary chamber; baffles staggered across said secondary chamber for diverting air drawn from said first mentioned chamber through the perforations in said panel into secondary chamber, said panel being adapted to support a quantity of water thereon without it appreciably leaking through said perforations but allowing air under pressure to pass upwardly through the panel and water and be humidified thereby and tempered by evapo-

ration before continuing by the baffles; a main inlet for supplying air to the distributing chamber, a main outlet for the outflow of the tempered and humidified air, and a device for inducing the air to flow through the chambers from the main inlet to the main outlet under pressure, with the addition of a tubular coil disposed in the secondary chamber to be immersed by said water, connections between the said outlet and said coil for transmitting the tempered air therethrough and an additional outlet for exteriorly dispersing the air after it passes through the coil with the addition of a valve for selectively controlling the passage of the tempered air through the coil and to the exterior atmosphere with the addition of means for supplying and draining the water in the secondary chamber and means for automatically controlling the supplying means with the device for inducing the air flow including a vacuumatic mechanism adjacent the main outlet and connected therewith to produce a suction within the cabinet to draw air from the main inlet through the distributing chamber, the perforations 20 in the panel, through the water into the space above in the secondary chamber, against the baffles to remove

excess particles of water and collect and drain them back into the water, and thence to the main outlet with the said baffles being horizontally positioned and including holes therethrough to facilitate the draining of the water particles collecting thereon, and the main inlet being disposed centrally in the bottom wall of the cabinet and the main outlet in the top wall of the cabinet offset to create a longer path between the baffles for the air flow whereby the flow of air therein will be zigzagged vertically upward.
